DESIGN FOR A LUBRICATOR CABINET

Thomas L. Hand, Cincinnati, Ohio, assignor to
The Cincinnati Ball Crank Company, Cincinnati, Ohio

Application July 11, 1941, Serial No. 102,035

Term of patent 3½ years

To all whom it may concern:

Be it known that I, Thomas L. Hand, a citizen of the United States and resident of Cincinnati, in the county of Hamilton and State of Ohio, have invented a new, original, and ornamental Design for a Lubricator Cabinet, of which the following is a specification, reference being had to the accompanying drawing, forming a part thereof.

The figure of the drawing is a perspective view of a lubricator cabinet showing my new design.

I claim:

The ornamental design for a lubricator cabinet, substantially as shown.

THOMAS L. HAND.
